(74) *Attorney, Agent, or Firm* — Dinsmore & Shohl LLP

(57) **CLAIM**

The ornamental design for a watch case, as shown and described.

DESCRIPTION

FIG. 1 is a perspective view of the rear, top and one side of a first embodiment of the watch case;

FIG. 2 is a side elevation view of the watch case of FIG. 1;
FIG. 3 is an opposite side elevation view of the watch case of FIG. 1;

FIG. 4 is a front elevation view of the watch case of FIG. 1;
FIG. 5 is a rear elevation view of the watch case of FIG. 1;
FIG. 6 is a top plan view of the watch case of FIG. 1;
FIG. 7 is a bottom plan view of the watch case of FIG. 1;
FIG. 8 is an exploded perspective view of the front, top and side of the watch case of FIG. 1;

FIG. 9 is a perspective view of the rear, top and one side of a second embodiment of the watch case;

FIG. 10 is a side elevation view of the watch case of FIG. 9;

FIG. 11 is an opposite side elevation view of the watch case of FIG. 9;

FIG. 12 is a front elevation view of the watch case of FIG. 9;

FIG. 13 is a rear elevation view of the watch case of FIG. 9;
FIG. 14 is a top plan view of the watch case of FIG. 9;
FIG. 15 is a bottom plan view of the watch case of FIG. 9; and,

FIG. 16 is an exploded perspective view of the front, top and side of the watch case of FIG. 9.

The broken lines show a strap for displaying the environment in which the design is associated and form no part of the claimed design.

1 Claim, 16 Drawing Sheets
